UNITED STATES PATENT OFFICE.

HALBERT K. HITCHCOCK, OF PITTSBURGH, PENNSYLVANIA, ASSIGNOR OF ONE-HALF
TO HITCHCOCK EXPERIMENT COMPANY, A CORPORATION OF NEW JERSEY.

PROCESS AND APPARATUS FOR MAKING SHEET GLASS.

Application filed December 9, 1924. Serial No. 754,754.

To all whom it may concern:

Be it known that I, HALBERT K. HITCHCOCK, a citizen of the United States, and a resident of Pittsburgh, in the county of Allegheny and State of Pennsylvania, have made a new and useful invention in Improvements in a Process and Apparatus for Making Sheet Glass, of which the following is a specification.

The invention relates to the continuous formation of sheet glass by withdrawing it vertically from a tank or receptacle, and constitutes an improvement over the construction shown in my application, Serial No. 606,388, filed Dec. 12, 1922. The present invention, as in the application referred to, utilizes gravity to secure the necessary feeding and stretching action upon the glass sheet, and provides for turning it laterally and feeding it through a horizontal leer instead of carrying it through a vertical leer. The invention has for its primary objects, the provision of an improved construction wherein a flat sheet is secured requiring no grinding or polishing and the provision of improved means for adjusting or regulating the gravity feed upon the sheet whereby the desired thickness of sheet and speed of draw may be secured.

Briefly stated, the invention contemplates the employment of a vertically adjustable secondary tank fed from the main melting tank, such secondary tank being the one from which the gravity formation of the sheet occurs. By adjusting the vertical position of the secondary tank, the length of ribbon or sheet between the drawing slot of the tank and the level of the leer is correspondingly changed, thus varying the drawing effect as imposed by gravity. This adjustment may be employed to vary the speed of draw and the thickness of the glass sheet or ribbon to suit conditions and requirements, the sheet in this case, as in that illustrated in my application referred to, being received upon a gravity runway after the glass has set to a point where it will not mar, and being conducted from this runway into the horizontal leer through which the glass is conducted continuously for annealing and cooling. The secondary tank is also preferably so arranged that it may be tilted, thus giving an additional means for

controlling the gravity flow from the outlet slot, although in normal operation, this tank will be maintained in a horizontal position. One embodiment of the invention is illustrated in the accompanying drawings wherein:

Figure 1 is a vertical section through the improved construction on the line I—I of Fig. 2. Fig. 2 is a vertical section taken on the center line of the apparatus in a plane at right angles to that of Fig. 1. Fig. 3 is a partial horizontal section taken on the line III—III of Fig. 4. And Fig. 4 is a vertical section similar to that of Fig. 2, but with the secondary tank at a lower level than in Fig. 2 and with such tank tilted slightly from the horizontal in order to stop the flow of glass from the outlet slot.

Referring to the drawings, 1 is the front end of a melting tank preferably of the re-generator type supported upon the foundation 2 of commercial sections and provided with an outlet slot or opening 3 for continuously withdrawing the glass from the tank by gravity. The glass discharges into a closed outlet trough 4 over the drain lip 5, the amount of discharge being controlled by the gate 6 operated from the screw 7 having a suitable hand wheel 8. When it is desired to completely shut off the flow of glass from this tank, the water cooled gate 9 is employed, such gate being operated from an overhead crane (not shown) by means of the chains 10. The outlet portion of the tank is preferably supported by the casting 11 mounted upon the base or framework 2.

The outlet spout 4 is closed in by a cover portion 12 and any additional heat necessary is supplied by the burners 13—13 carried by the spout and supplied with gas through the flexible pipe 14. The spout consists of a metal shell 15 with a lining 16 of refractory material, such as clay and is pivotally connected at its rear end to the casting 11 as indicated at 17. The forward end of the spout is pivotally supported upon a casting 18 by means of the pair of links 19, such pivotal arrangement of the trough serving to permit it to follow the vertical movements of the secondary tank, which will now be described.

The secondary tank 20 into which the spout discharges and from which the draw-

17 adjacent the point at which the stream of glass from the melting tank strikes the bottom of the trough, so that the up and down movements of the trough, due to adjusting the position of the secondary tank, causes substantially no disturbance at this point, and so that the clearance space between the bottom edge of the spout 5 and the bottom of the trough is not varied so as to disturb the cooling effect at this point.

18 What I claim is:

19 1. In combination in apparatus for forming sheet glass, a melting tank, a secondary tank in position to receive a gravity flow 25 of molten glass from the melting tank, mounted for vertical movement, and provided with a discharge slot directed downwardly, means below the slot for receiving and turning laterally the ribbon of glass 30 discharged through the slot, and a horizontal leer in position to receive the ribbon from said means and provided with means for carrying it therethrough.

20 2. In combination in apparatus for forming sheet glass, a melting tank, a secondary tank in position to receive a gravity flow of molten glass from the melting tank, mounted for vertical movement, and provided 35 with a discharge slot directed downwardly, a curved runway positioned below said slot so as to receive the ribbon of glass discharged through said slot and to turn it laterally, and a horizontal leer in position to receive the ribbon from the runway and 40 provided with means for carrying it therethrough.

45 3. In combination in apparatus for forming sheet glass, a melting tank, a secondary tank in position to receive a gravity flow 50 of molten glass from the melting tank, having a discharge slot through its bottom, lifting means upon which the secondary tank is mounted so that it may be adjusted vertically, means below the slot for receiving and turning laterally the ribbon of glass discharged through the slot, and a horizontal leer in position to receive the ribbon from 55 said means and provided with means for carrying it therethrough.

60 4. In combination in apparatus for forming sheet glass, a melting tank, a secondary tank in position to receive a gravity flow of molten glass from the melting tank, having a discharge slot through its bottom, lifting means upon which the secondary tank is mounted so that it may be adjusted 65 vertically, and also tilted, means below the slot for receiving and turning laterally the ribbon of glass discharged through the slot, and a horizontal leer in position to receive the ribbon from said means and provided with means for carrying it therethrough.

65 5. In combination in apparatus for forming sheet glass, a melting tank, having a gravity discharge outlet, a secondary tank

70 below the first tank, means for moving such tank vertically, a spout arranged to receive the molten glass from said outlet and conduct it to the secondary tank, a discharge outlet from the secondary tank, a runway 75 extending downwardly and laterally in position to receive the glass sheet or ribbon from said outlet from the secondary tank, and a horizontal leer in position to receive said sheet or ribbon from the runway.

75 6. In combination in apparatus for forming sheet glass, a melting tank, having a gravity discharge outlet, a secondary tank below the first tank, mounted for vertical adjustment, a spout positioned so as to receive the glass from said outlet and conduct it into the secondary tank, said spout being pivotally mounted to permit it to adjust itself to the movements of the secondary tank incident to its adjustment, a gravity 80 discharge slot leading downwardly from the secondary tank, a horizontal leer below said outlet, and means for conducting the glass withdrawn from said slot continuously into and through the leer.

85 7. A process of making sheet glass continuously which consists in withdrawing the molten glass continuously from a melting tank to a secondary tank, withdrawing the glass in said secondary tank continuously therefrom in a vertical sheet or ribbon, allowing said sheet to stretch of its own weight, and while it is still plastic turning such sheet laterally, and finally carrying it continuously through a horizontal leer.

90 8. A process of making sheet glass continuously which consists in withdrawing the molten glass continuously from a melting tank to a secondary tank, withdrawing the glass in said secondary tank continuously 95 therefrom in a vertical sheet or ribbon, allowing said sheet to stretch of its own weight, and while it is still plastic turning such sheet laterally, and finally carrying it continuously through a horizontal leer, the said secondary tank being adjusted 100 vertically to vary the weight of the vertical portion of the sheet.

105 9. A process of making sheet glass continuously which consists in withdrawing the molten glass continuously from a melting tank to a secondary tank, withdrawing the glass in said secondary tank continuously 110 therefrom in a vertical sheet or ribbon, allowing said sheet to stretch of its own weight, and while it is still plastic turning such sheet laterally, and finally carrying it continuously through a horizontal leer, the rate of draw incident to the weight of the sheet below the secondary tank being adjusted 115 by raising and lowering the secondary tank.

120 10. In combination in apparatus for forming sheet glass, a melting tank, a secondary tank in position to receive a gravity 125

- flow of molten glass from the melting tank, mounted for vertical movement, and provided with a discharge slot directed downwardly, means below the slot for receiving and turning laterally the ribbon of glass discharged through the slot, a horizontal leer in position to receive the ribbon from said means, and means for applying heat to the glass in said secondary tank.
11. In combination in apparatus for forming sheet glass, a melting tank, having a gravity discharge outlet, a secondary tank below the first tank, means for moving such tank vertically, a spout having a closure over its top arranged to receive the molten glass from said outlet and conduct it to said secondary tank, means for applying heat to the glass as it flows through said trough, a discharge outlet from said secondary tank, a runway extending downwardly and laterally in position to receive the glass sheet or ribbon from said outlet from the secondary tank, and a horizontal leer in position to receive said sheet or ribbon from the runway.
12. In combination in apparatus for forming sheet glass, a melting tank, having a gravity discharge outlet, a secondary tank below the first tank, mounted for vertical adjustment, a spout positioned so as to receive the glass from said outlet and conduct it into the secondary tank, said spout being pivotally mounted to permit it to adjust itself to the movements of the secondary tank incident to its adjustment, a gravity discharge slot leading downwardly from the secondary tank, a horizontal leer below said outlet, and means for conducting the glass withdrawn from said slot continuously into and through the leer, the said spout having its discharge end extended to a point below the level of the glass in the secondary tank and arranged so that it is maintained below such level when said tank is adjusted up and down.
13. In combination in apparatus for forming sheet glass, a melting tank, having a gravity discharge outlet, a secondary tank below the first tank, means for moving such tank vertically, a spout having a closure over its top arranged to receive the molten glass from said outlet and conduct it to said secondary tank, means for applying heat to the glass as it flows through said trough, means for applying heat to the glass in the secondary tank, a discharge outlet from said secondary tank, a runway extending downwardly and laterally in position to receive the glass sheet or ribbon from said outlet from the secondary tank, and a horizontal leer in position to receive said sheet or ribbon from the runway.
14. In combination in apparatus for forming sheet glass, a melting tank, having a gravity discharge outlet, a secondary tank below the first tank, mounted for vertical adjustment, a spout positioned so as to receive the glass from said outlet and conduct it into the secondary tank, said spout being pivotally supported at its upper end to permit it to adjust itself to the movements of the secondary tank incident to its adjustment, and at a point such that the glass from the melting tank is always received at substantially the same point in the trough, a gravity discharge slot leading downwardly from the secondary tank, a horizontal leer below said outlet, and means for conducting the glass withdrawn from said slot continuously into and through the leer.
- In testimony whereof, I have hereunto subscribed my name this 21st day of Nov., 1924.

HALBERT K. HITCHCOCK.
